CLAIM

The ornamental design for a boot, as shown and described.

DESCRIPTION

FIG. 1 is a rear view of a boot, showing my new design;

FIG. 2 is a right side view thereof;

FIG. 3 is a left side view thereof;

FIG. 4 is a top view thereof;

FIG. 5 is a front perspective view thereof;

FIG. 6 is a rear perspective view thereof;

FIG. 7 is a front view thereof;

FIG. 8 is a rear and bottom perspective view thereof;

FIG. 9 is a front and bottom perspective view thereof;

FIG. 10 is a left side and bottom perspective view thereof;

and,

FIG. 12 is another front and bottom perspective view thereof.

Broken lines illustrate portions of the boot that form no part of the claimed design.

1 Claim, 12 Drawing Sheets
